UNITED STATES PATENT OFFICE.

OTTO H. MEYERS, OF NEW YORK, N. Y.

SHADE-BRACKET.

1,234,064.

Specification of Letters Patent. Patented July 17, 1917.

Application filed October 29, 1915. Serial No. 58,652.

To all whom it may concern:

Be it known that I, OTTO H. MEYERS, a citizen of the United States, residing at New York, in the county of New York and State of New York, have invented certain new and useful Improvements in Shade-Brackets, of which the following is a specification.

This invention relates to improvements in curtain or shade brackets, one object of the 10 invention being the provision of a device, the members of which are each provided with a hinged curtain or shade spindle receiving member, whereby a roller may be supported within or without the window frame, and 15 also whereby two lengths of roller may be supported without using different brackets.

A further object of the present invention is the provision of a shade bracket having a 20 supporting member for attaching the bracket to the window frame, the shade supporting member being hinged thereto, so that the shade may be supported when the hinged supporting member is in a vertical or horizontal position, thus adapting the device for 25 use upon long and short roller.

In the accompanying drawings:

Figure 1 is a view in elevation of the upper portion of a window frame with a shade roller supported within the frame.

30 Fig. 2 is a similar view with the shade supported exteriorly of the frame.

Fig. 3 is a view showing the brackets in use.

Figs. 4 and 5 are perspective views of the 35 two members of each of the brackets.

Referring to the drawings, the numbers 5 and 6 designate the two brackets, used to support the shade rollers 7 and 8.

Both of the brackets are identical except 40 that one is for supporting the flattened spindle of the roller, as is usual, and the other is for supporting the cylindrical spindle.

Each bracket comprises the head 9, having the supporting fastening 10, here shown a 45 screw, while upon the opposite side is the lug 11, the outer end of which is rounded at one side edge. Removably mounted in the lug 11 is the hinging pin 12. The other member or wing 13, is provided on the opposite side 50 edges adjacent the inner end with the spaced

parallel ears 14, which project at right angles from the wing and have their outer side edges arranged in the plane of the edge of one end of the wing. The ears 14 straddle the lug 11, and are pivotally engaged by 55 the hinging pin 12, so that the wing 13 is arranged adjacent the rounded edge of the lug in order that it may be swung to assume the position as shown in Fig. 1 or the positions shown in Figs. 2 and 3. In the wing 60 14, near its outer end is provided the two shade trunnion receiving slots 15 and 16, the slots 15, supporting the shorter roller 7, as shown in Fig. 1, while the slots 16, support the trunnions of the roller 8, as shown in 65 Fig. 2.

Thus by the use of a bracket of this character the screw 10, may be attached to the inner or outer face of the window frame, and the shade supporting wing 13, may be swung 70 to abut the outer edge of the lug and assume the positions as illustrated in Fig. 1 or else it may be swung so that the outer straight side edges of the ears abut the head as illustrated in Figs. 2 and 3. 75

In order that the head 9 may be driven by a screw driver, the slot a is provided in the lug 11, as shown in Figs. 4 and 5.

What I claim as new is:

A shade bracket including a head adapted 80 to be attached to a window casing, a lug projecting from the head and having a portion of the outer edge rounded toward one side edge, a flat elongated wing having trunnion supporting means in the outer end, ears 85 formed on the side edges of the wing at the opposite end and projecting at right angles therefrom and having their outer straight side edges arranged in the plane of the edge of the inner end of the wing, and a pin for 90 pivotally connecting the ears upon opposite sides of the lug so that the inner surface of the wing is arranged adjacent the rounded edge of the lug to permit of the wing being 95 swung to abut the outer edge of the lug or else swung so that the outer straight side edges of the ears will abut the head.

In testimony whereof I affix my signature.

OTTO H. MEYERS.
